(57) **CLAIM**

The ornamental design for a charging holder for vacuum cleaner, as shown and described.

DESCRIPTION

FIG. 1 is a front perspective view of a charging holder for vacuum cleaner, showing our new design;

FIG. 2 is a front view thereof;

FIG. 3 is a rear view thereof;

FIG. 4 is a left-side view thereof;

FIG. 5 is a right-side view thereof;

FIG. 6 is a top plan view thereof;

FIG. 7 is a bottom plan view thereof;

FIG. 8 is a bottom rear perspective view thereof;

FIG. 9 is an enlarged view of the delineated portion 9 in FIG. 1;

FIG. 10 is an enlarged view of the delineated portion 10 in FIG. 2; and,

FIG. 11 is an enlarged view of the delineated portion 11 in FIG. 2.

The evenly dashed broken lines in the figures depict portions of the charging holder for vacuum cleaner, and form no part of the claimed design.

The dot-dash broken lines delineating portions of the claimed design that are illustrated in enlargements form no part of the claimed design.

1 Claim, 11 Drawing Sheets
